SELECTIVE-CONTROL MECHANISM FOR PRINTING MACHINES.

Application filed July 31, 1924. Serial No. 729,203.

My present invention is primarily designed for and is shown as embodied in a flat bed printing machine, in which a set of platens carry printing blocks which impress a design on a base material such as linoleum, oil cloth, or impregnated felt which is fed, step by step, beneath the successive printing platens. Where the pattern is in more than one color, it is common to have successive platens of the same set each print with a different color upon the same area or length of the base material, the length of each said area being equal to the length of one step of the intermittent feed of the base material. Where the design is a simple repeating design, only one set of platens is necessary and there are no complications, but where the design varies lengthwise of the base material as, for instance, in printing rugs with border designs, there must be at least two sets of the printing platens, one set for the body and side border areas, which may be repeated as many times as desired, and another set which will print a different design, represented by the two end borders of two adjacent rugs. For simplicity, only two sets of printing platens are assumed, one for a repeating body design which may be repeated as many times as required for the length of the rug, and another set for the end joint and cross-borders between rug patterns.

Where two sets of printing platens are used, it is necessary to have the repeat patterns for the body portion of the rug repeated the number of times required for a desired length of rug, and to have each platen of the set thrown out so as not to print when the space required for a cross-border comes under it. Corelatively, the cross-border set of platens must be controlled so that they will print successively a single stroke upon the cross-border space left vacant by the body printing set when said space registers under said platen and will be thrown out and remain idle while the succession of body printed spaces pass under it.

For instance, for a four-color rug, the body printing set will comprise four platens, each printing a different color and each delivering the desired number of repeat impressions upon successively fed areas of the base material, but after each has printed said

predetermined number of strokes, it will be thrown out to leave a blank space for the border printing set to print upon. Thus for a three repeat, the body printing platen No. 1 will print on three successive feeds and will throw out one feed. No. 2, operating after No. 1, by an interval assumed to be one feed step, will print three successive times on the spaces printed by No. 1 and will throw out when a blank space reaches it. Similarly, Nos. 3 and 4, operating respectively two and three intervals or feed steps after No. 1, will each print three times and will throw out when a blank space reaches them. Next, the material will be under No. 1 platen of the cross-border set, which must throw into operate one stroke at that time and then throw out while three body printed sections pass under it. Next, the cross-border partly printed by platen No. 1 of the border printing set will pass under platen No. 2 of the border printing set, which will then print one stroke and throw out three strokes. On the next feeds, platens Nos. 3 and 4 of the border printing set will each print once and then throw out three.

In machines of this type the printing strokes of the platens are by gravity regulated by rotary cams upon which the platens rest, and there are swinging detent hooks which are thrown in to support the weight of the printing platens and prevent a printing stroke, when desired, the cams or other actuating means for the platens operating continuously as if to print between all steps of the intermittent feed. The novel mechanism which I employ for selectively controlling the movement of the detent hooks includes a step by step detent controlling mechanism synchronized with the step by step feed and print mechanisms and preferably driven from the platen actuating means. This detent controlling mechanism includes means for rendering the detent hooks operative or inoperative, at the end of a predetermined number of steps. In other words, my improved selector mechanism serves as a timer for rendering the detent hook operative or inoperative after the platens have been active or inactive for the desired number of strokes.

An important feature is means whereby the successive platens can have their detent intervals set so that they will print and

throw out in proper phase relation as required by the design; and also may be so set for a different number of repeats for the body printing set of platens, to make longer or shorter rugs of the same pattern.

The invention may be better understood from the following description in connection with the accompanying drawings, wherein—

Fig. 1 is a fragmentary view in side elevation of a printing machine equipped with my selector mechanism.

Fig. 2 is a sectional detail on the line 2—2 of Fig. 3.

Fig. 3 is a plan view of the selector mechanism and its associated parts.

Fig. 4 is an enlarged view in side elevation of the mechanism shown in Fig. 3.

Fig. 5 is a plan view of the selector ratchet.

Figs. 6 and 7 are diagrammatic views showing the relative positions of the ratchet wheels, cams and cover plates when the selector mechanisms are set for three repeats and seven repeats respectively where there is but one feed step between repeats.

Fig. 8 is a diagram like Fig. 7, but indicating the spacing and phase adjustments where there are two feed steps between repeats.

Fig. 9 is a schematic view supplemental to Figs. 6, 7 and 8, indicating that a plurality of the platens and control mechanism of Figs. 1 to 4 are used in combination with a step by step feed mechanism.

The printing machine includes side frame members 10, 10, the upper of which mounts a guideway 11 for a vertically reciprocating slide 12 supporting one end of a printing platen 13 which carries printing blocks 14 of suitable pattern. The opposite end of the platen 13 is similarly supported by a similar cross head and any appropriate number of like platens may be arranged side by side or at distances apart determined by the length of step of the intermittent feed of the linoleum or other material to be printed upon. The feeding mechanism for the material, the means for inking the platens and other such conventional details have been omitted from the drawings for the sake of clearness.

The lower frame members 10 provide bearings for the ends of a cam shaft 15, mounting cams 16 engaging with rollers 17 at the lower ends of the slides 12 to effect vertical reciprocation of the platens. Detent hooks 18 are movable into position to block the downward movement of the slides 12 and consequently to selectively render any of the platens inactive in spite of the continuous rotation of their lifting cams 16.

The machine as thus far described may be of any known or desired construction usable for such purposes, and the present invention relates more specifically to means actu-

ated from the cam shaft 15 and selectively controlling the positions of the detent hooks 18. Such mechanism may conveniently include a counterweight 19 normally tending to hold the detent out of the path of the slide, and a lever 20 carrying the detent and adapted to be moved by link 21 to swing the detent into latching position against the action of the counterweight. The link is actuated by a rocking lever 22 controlled by a retracting cam 23 rotated by the ratchet wheel 24 which is intermittently driven from the cam shaft 15. It will thus be seen that if cam 23 is provided with a single projection, it will operate through the lever 22, link 21 and lever 20 to swing a detent to locking position once every rotation of the cam and ratchet wheel. If, however, the cam is designed so that it has a depression instead of a projection, the mechanism will serve to normally lock the platen against movement to printing position and will permit such movement only once per revolution of the cam and ratchet. In order to properly predetermine and control the movement of the platen, I employ a variable feed mechanism for the ratchet wheel. This mechanism serves to rotate the ratchet wheel, one step for every feed operation of the machine and by varying the number of steps necessary to complete a revolution the number of successive repeats during such revolution may be selectively predetermined.

The ratchet wheel 24 and cam 23 are preferably rigid with a common hub 25 which turns upon a stub shaft 26 projecting laterally from a supplemental frame member 27 secured in any appropriate manner (not shown) to the lower frame member 10. This frame member also mounts a depending bracket 28 to which the lower end of the rocking lever 22 is pivoted as at 29, said lever being pivotally connected at 30 to the link 21 and carrying intermediate its ends a roller 32 which is held against the cam 23 by the counterweight 19. A pivotal connection such as that indicated at 33 serves for the connection of the link 21 and the lever 20 carrying the detent hook. For effecting step by step movement of the ratchet wheel, I employ an arm 35 integral with a sleeve 36 which oscillates on the common hub 26 of the cam and ratchet wheel. The arm 35 carries a pawl 37 at its free end for engaging with the teeth or notches in the periphery of the ratchet wheel and is oscillated through an arc of approximately 90 degrees by a connecting rod 38 driven from a disk 39 fixed to the cam shaft 15.

In machines of this character the time allowed for the introduction of the hooks which hold up the printing platens is momentary and it is found expedient to have the cams working a little in advance of the engagement or release of the hooks and

with this in view I may employ spring 50 encircling the end of the pull bar 21 and bearing against the end of the rocking lever 22. This spring in connection with an adjusting nut 51 working on a threaded portion 52 of the pull bar may be utilized for effecting a sliding adjustment of the end of the rocking lever on the pull bar to finely time the movement of the pull bar relative to the movement of the printing cam 16.

The ratchet wheel is equipped with a plurality of sets of teeth, the teeth of the several sets being spaced different equi-distances from each other about the periphery of the ratchet. In the case assumed, that is, when the machine is adapted for printing anywhere from three to nine repeats of the body of the rug, there will be four teeth 90 degrees apart, five teeth 72 degrees apart, six teeth 60 degrees apart, ten teeth 36 degrees apart, etc. With the form of device shown, the reciprocatory rocking movement of the pawl carrying crank is through a distance at least equal to and preferably slightly greater than the greatest distance between the teeth of the most widely spaced set of the ratchet wheel, namely a rocking movement of slightly more than 90 degrees. Some of the teeth in the different sets may be identical as, for instance, the eight step set will utilize all of the teeth of the four step series and will require only four additional teeth, one midway between each of the teeth of the four tooth set.

The tooth set numbering of the Figure 5, wherein the numerals for sets correspond to the number of teeth in its set, indicates clearly that various teeth are common to a number of sets and the zero notch is common to all sets.

It will be noted that the cams of each ratchet wheel bear a similar relation to the zero notch of such wheel and that by proper angular adjustment of the zero notches relative to each other, the cams of a printing set will be properly adjusted. It may thus be found expedient to display some readily visible indication which will facilitate the rapid identification of the zero notch of each wheel and consequently expedite changing a setting.

The ratchet pawl reciprocating at all times through an arc of 90 degrees, one reciprocation for each feed of the base material being printed upon, will naturally bring the controlling detent hook into operative relation with its printing plates during one stroke in every four, thus effecting three repeats and one throw-out for the platen.

In order to adjust this mechanism so that the pawl will act on any of the series of teeth, I provide a cover plate 40 turning freely on the stud shaft 26 and carrying an arcuate lip 41 which extends over and conceals approximately one-fourth of the per-

iphery of the ratchet wheel. This cover plate is adjusted to cover a desired extent of the initial portion of the stroke of the feeding pawl which will thus ride up on the cover and slide idly for any desired portion of its feeding stroke. For locking the cover in any adjusted position I employ a locking plate 42 keyed upon the shaft 26 and having a series of notches 43 in its edge which may be selectively engaged by a locking handle 44. Handle 44 serves to lock the cover plate against movement of its shaft and also affords means for manually turning the plate to change the adjustment thereof. A cross bar 45 fixed to the end of the stud shaft 26 carries a pair of inwardly presented studs 46. Springs 47 encircling the studs exert pressure on the locking plate 42 and tend to urge the cover plate flat against the face of the ratchet wheel. The cover plate thus serves as a brake effectively damping the movement of the ratchet wheel under the impetus of its actuating pawl. Furthermore, such braking action overcomes the tendency of hub 25 to turn with the bearing sleeve 36 of the arm 35.

For purposes of illustration, I have diagrammatically shown the sets of cams for the body printing mechanism and the border printing mechanism of a rug set at two different adjustments. In Fig. 6, the cams and ratchets are shown as set for printing a rug in four colors with a body length of three repeats. In Fig. 7, they are shown as set for printing a rug in four colors with a body length of seven repeats. In setting for three repeats, the first ratchet wheel will be rotated until its zero tooth is in the position indicated in Fig. 4. The cover plate is then adjusted until its front edge just exposes the next or 4th tooth of the series in question. As the operation of the machine is started, the pawl passing forward over the cover plate will drop into the first tooth exposed and only the remainder of the stroke will be operative as a feed stroke for the ratchet wheel. By setting the cover plate, the ratchet may be rendered operative only for the desired fourth, fifth, sixth, or seventh or tenth portion of a revolution, but said portion of a revolution, whatever it is, will bring the next tooth of that particular series into position where it will be just uncovered by the front edge of the cover plate and will be engaged by the ratchet on its next forward stroke.

In setting the next ratchet wheel of the series, for a three repeat rug, it must be borne in mind that it is not merely necessary for the pawl to work in the series of four teeth but also that the cams associated with the two ratchet wheels bear a proper angular relationship to each other so that the successive platens will be successively held out to permit the passage of an un-

printed border portion thereunder. In Fig. 6, I have indicated the proper relations of the successive cams when the machine is ready to print a three repeat rug with only one feed step between repeats. It will be noted that the successive cams are at angles of 90 degrees apart and that the teeth just exposed by the edges of the series of cover plates are 4^a , 0, 4^c , 4^b , respectively. For 10 two feed steps between repeats, the successive cams must be set 180 degrees apart, that is, two steps or teeth instead of one. The desired number of repeats and throw-outs and the timing thereof for the first set of 15 platens being thus adjustably controlled, the corelative timing of the second set of border printing platens may be predetermined by precisely similar mechanism except that the throw-out cam 23^a of the latter is corelative 20 to the body printing cams 23. That is to say, the detent portion of the cam extends around all of the circumference where the cam 23 has a depression and has a depression where the cam 23 has a projection.

25 With the cams set as indicated at Fig. 6, it will be evident that as a rug is fed through the machine the first platen will print its color three successive times and then remain inactive to permit the passage 30 of a border space thereunder. The other body printing platens will be similarly controlled and timed to remain inactive as the border space passes under them. The set of border printing platens on the other hand 35 remain inactive while the three printed repeats of the body portion of the rug pass beneath them and operate successively up on the space left blank for a border.

In changing the adjustment of the machine 40 so that it will print a rug having the same pattern but having a considerably longer body portion as, for instance, seven repeats instead of three, the ratchet wheels are set to the position indicated in the Fig. 45 7 so that the 8^a tooth of the first ratchet will be just exposed by the cover plate. It will be noted that with this adjustment the cover plates for the ratchets render the first half 50 of the feed stroke of the pawl inoperative so that the step by step movement of the ratchet requires eight reciprocations of the pawl to effect a complete revolution. In other words, the body printing platens will print on seven strokes and remain inactive 55 on the eighth while the reverse is true of the border printing platens. Attention is called to the fact that while simply shifting the cover plates from the position of Fig. 7 will suffice for properly changing the adjustment 60 of the ratchets, it will not put the throw-outs of successive platens in proper relation of succession or phase. This is because the cams for printing a seven repeat rug must be arranged at successively varying angles of 45 degrees instead of 90 de-

grees. Thus, the setting of the ratchet wheels involves not only the shifting of the cover plates, but also manual over-running of the ratchet wheels to move the cams into proper corelative relationship. In each instance, one of the teeth of the eighth series will be just exposed by the forward edge of the cover plate but the zero teeth of the various wheels, and consequently the cams, must follow each other at intervals at 45 degrees 75 instead of 90 degrees in the case of the set up for the three repeat rugs. In other words, for a seven repeat rug the cover plates are disposed in a common position but the teeth exposed by the cover plate 80 edges must be 8^a , 0, 8^c , 8^b , respectively, and such adjustment when changing from a set up for three repeats necessarily involves overrunning the ratchets as well as shifting the covers. The manner of changing the 85 set up for printing four, five, six and nine repeat rugs will be apparent.

The showing of four platens in connection with the body printing mechanism and the border mechanism is entirely arbitrary since 90 the number of platens of each set depends entirely upon the number of colors in which the rug is to be printed and has nothing whatever to do with the number of repeats. As a matter of fact, the mechanism illustrated 95 might be readily adapted for printing in one, two or three colors since one, two or three platens of each set could be rendered continuously inactive by shifting the cover plate of their respective ratchet wheels 100 to such a position that the feed stroke of the pawls would be entirely idle and the pawls would slide on the cover plate instead of turning the ratchet wheels. If, on the other hand, one of the platens carried a design 105 which was common to both body repeats and border, such platen could be rendered continuously active by similar adjustment of the cover plate but with the cam 23 in its hold out position of Fig. 4.

It will be evident from the foregoing description of the adjusting means that almost any desired range of repeats and throw-outs may be obtained by suitably designed cams and ratchet wheels subject only to practical 115 limitations such as the sizes of the cams and ratchet wheels which would be required if too great a selective range were attempted. The selective range illustrated is adequate for all practical purposes permitting the 120 printing of rugs from three to nine repeats except for the omission of the eight repeat which is considered a non-standard size.

The control mechanism is adaptable for 125 single step feed between platens or for spacing and two, three or more step feeds between platens. The only difference is that the two or more step spacing requires overrunning of more of the teeth of the successive ratchets, so that the cams instead of being each one 130

step behind the other, are two, three or more steps behind, as the case may be. It will be understood that in actual commercial practice the platens are spaced at intervals of 5 two feed steps, so as to allow spaces between the platens for the color boxes of each, which must pass under the plates to ink them between each printing stroke thereof, and must be out of the way when the printing stroke 10 occurs. To illustrate, I have shown in Fig. 8, a diagram for a body printing set of four platens adjusted for seven repeats and one throw-out, with two feed steps between the platens. It will be evident that the only 15 difference between the adjustment for the one step feed as shown in Fig. 7 and the two step adjustment shown in Fig. 8 is that in Fig. 8 the successive cams are each two teeth or a 90 degree angle behind the preceding 20 cam, whereas, in Fig. 7 they are each only one tooth or 45 degrees behind the preceding cam.

All of the above diagrams showing phase 25 relations of the feed mechanism presuppose a plurality of the units shown in Fig. 1, including a succession of the platens 14. This fact is illustrated in Fig. 9, where a succession of units like Fig. 1, are schematically 30 indicated as associated with feed mechanism commonly employed in this way, as for instance, the belts 60, having pins 61 engaging the edges of the oilcloth and other fabric, these being given the required step by step 35 intermittent feed by any suitable mechanism, conventionally indicated as including a pawl 62, engaging a ratchet wheel 63, the ratchet being rigid with the carrier drum of the pin belt and the pawl rigid with a gear 64, engaged by a rack 65, reciprocated through 40 a link 66, by suitably driven crank disc 67.

While the invention possesses certain features of particular advantage in connection with controlling the platen operation of oil cloth, saturated felt and linoleum printing 45 machines and the like, it may have a more extended application to the control of various types of intermittently operating or repeating stroke mechanisms, particularly machines for stamping, embossing, perforating, cutting, etc., materials of various kinds for 50 various purposes. Certain of the novel combinations of coacting elements form mechanical movements of even wider applicability.

I claim:

55 1. A machine for printing upon sheets of linoleum, oil cloth, impregnated felt, and the like, including means for feeding lengths of the material, a set of platens operating successively to print a varicolored design on selected lengths of said material, another set of platens operating successively to print another varicolored design on other selected 60 lengths of said material, throw-out mechanisms associated with each platen of said first set and automatically operable to successively retain such printing platens in inactive position during the passing thereunder of blank lengths to be printed by said second set of platens, other throw-out mechanism associated with each platen of said second set automatically holding said platens 65 of the second set inactive during the passage thereunder of lengths of the material that have been printed upon by said first set and permitting successive operation of 70 said platens of the second set on the lengths unprinted by said first set; and automatic controlling means for operating each of the throw-outs, each said controlling means including an intermittently rotated member 75 operable to actuate the throw-out mechanism a predetermined number of steps per throw-out operation and having an element associated therewith shiftable to different positions to predetermine the speed of the 80 rotated member and thereby to vary the number and timing of repeats printed by one of the sets of platens and the corelative number and timing of inoperative periods of the other set of platens whereby patterns 85 of varying lengths but having the same designs may be selectively printed.

2. A machine for printing upon sheets of linoleum, oil cloth, impregnated felt, and the like, including means for feeding lengths of the material, a set of platens operating successively to print a varicolored design on selected lengths of said material, another set of platens operating successively to print another varicolored design on other selected 90 lengths of said material, throw-out mechanisms associated with each platen of said first set and automatically operable to successively retain such printing platens in inactive position during the passing thereunder of blank lengths to be printed by said second set of platens, other throw-out mechanism associated with each platen of said second set automatically holding said platens 95 of the second set inactive during the passage thereunder of lengths of the material that have been printed upon by said first set and permitting successive operation of said platens of the second set on the lengths unprinted by said first set; and automatic controlling means for shifting all of the throw-outs, including periodically rotated members operable to actuate the throw-outs a predetermined number of steps per throw-out 100 operation, and means associated therewith adjustable to different positions to predetermine the speed of the rotated members and thereby to vary the number and timing of repeats printed by one of the sets of platens and the corelative number and timing of inoperative periods of the other set of platens whereby patterns of varying lengths but having the same design may be selectively printed.

3. A machine for printing upon sheets of 105 linoleum, oil cloth, impregnated felt, and the like, including means for feeding lengths of the material, a set of platens operating successively to print a varicolored design on selected lengths of said material, another set of platens operating successively to print another varicolored design on other selected 110 lengths of said material, throw-out mechanisms associated with each platen of said second set automatically holding said platens of the second set inactive during the passage thereunder of lengths of the material that have been printed upon by said first set and permitting successive operation of said platens of the second set on the lengths unprinted by said first set; and automatic controlling means for shifting all of the throw-outs, including periodically rotated members operable to actuate the throw-outs a predetermined number of steps per throw-out 115 operation, and means associated therewith adjustable to different positions to predetermine the speed of the rotated members and thereby to vary the number and timing of repeats printed by one of the sets of platens and the corelative number and timing of inoperative periods of the other set of platens whereby patterns of varying lengths but having the same design may be selectively printed.

3. A machine for printing upon sheets of 120 linoleum, oil cloth, impregnated felt, and the like, including means for feeding lengths of the material, a set of platens operating successively to print a varicolored design on selected lengths of said material, another set of platens operating successively to print another varicolored design on other selected 125 lengths of said material, throw-out mechanisms associated with each platen of said second set automatically holding said platens of the second set inactive during the passage thereunder of lengths of the material that have been printed upon by said first set and permitting successive operation of said platens of the second set on the lengths unprinted by said first set; and automatic controlling means for shifting all of the throw-outs, including periodically rotated members operable to actuate the throw-outs a predetermined number of steps per throw-out operation, and means associated therewith adjustable to different positions to predetermine the speed of the rotated members and thereby to vary the number and timing of repeats printed by one of the sets of platens and the corelative number and timing of inoperative periods of the other set of platens whereby patterns of varying lengths but having the same design may be selectively printed.

3. A machine for printing upon sheets of 130 linoleum, oil cloth, impregnated felt, and the like, including means for feeding lengths of the material, a set of platens operating successively to print a varicolored design on selected lengths of said material, another set of platens operating successively to print another varicolored design on other selected lengths of said material, throw-out mechanisms associated with each platen of said second set automatically holding said platens of the second set inactive during the passage thereunder of lengths of the material that have been printed upon by said first set and permitting successive operation of said platens of the second set on the lengths unprinted by said first set; and automatic controlling means for shifting all of the throw-outs, including periodically rotated members operable to actuate the throw-outs a predetermined number of steps per throw-out operation, and means associated therewith adjustable to different positions to predetermine the speed of the rotated members and thereby to vary the number and timing of repeats printed by one of the sets of platens and the corelative number and timing of inoperative periods of the other set of platens whereby patterns of varying lengths but having the same design may be selectively printed.

linoleum, oil cloth, impregnated felt and the like, including a set of platens operating successively to print a multi-colored body design on a sheet, another set of platens 5 operating successively to print a multi-colored border design on said sheet, detents associated with the body printing platens and automatically operable to successively retain such printing platens in inactive position 10 during the passage thereunder of a blank border space, other detents associated with the border printing platens automatically holding said platens inactive during the passage of a printed body portion thereunder 15 and permitting successive operation of the border platens on the border spaces; and automatic controlling means for shifting all of the detents, including rotatable members operable to shift the detents on every revolution and means, adjustable to vary the speed of the rotatable members and consequently the number of repeats printed upon the body portion and the number of inoperative periods of the other set of platens 20 25 whereby patterns of varying lengths and having the same design may be selectively printed.

4. A machine for performing different single stroke operations on successive lengths 30 of materials, including means for feeding lengths of said material, a set of single stroke devices operating successively to perform different operations on the same selected lengths of said material, another set of 35 single stroke devices operating successively to perform another set of different operations on other selected lengths of said material, throw-out mechanism associated with each single stroke device of said first set and 40 automatically operable to successively retain such device in inactive position during the passing thereunder of blank lengths to be operated upon by said second set of devices, other throw-out mechanism associated with 45 each single stroke device of said second set, automatically holding said devices of the second set inactive during the passage thereunder of lengths of the material that have been operated upon by said first set and to 50 permit operation thereof on the lengths unoperated upon by said first set; and automatic controlling means for shifting all of the throw-outs, said controlling means including step by step rotated members controlling the throw-outs and devices associated therewith, adjustable to different positions to vary the lengths of the steps and consequently the number and timing of repeats 55 by one of the sets of single stroke devices and 60 the corelative number of timing of inoperative periods of the other set whereby repeating operations on a varying number of the lengths of the material may be selectively performed.

5. A machine for performing different

single stroke operations on successive lengths of material, including means for feeding lengths of said material, a single stroke device operating to perform the operation on selected lengths of said material, another 70 single stroke device operating to perform a different operation on other selected lengths of said material, throw-out mechanism associated with the first single stroke device automatically operable to retain such device 75 in inactive position during the passing thereunder of blank lengths to be operated upon by said second device, other throw-out mechanism associated with the second single stroke device, automatically holding said device 80 inactive during the passage thereunder of lengths of the material that have been operated upon by said first device and to permit operation thereof on the lengths unoperated upon by said first device; an automatic controlling means for shifting the throw-outs, said controlling means including a rotatable element moved step by step and a device associated therewith, adjustable to different positions to predetermine 85 the distance which said element is moved at each step and consequently vary the number and timing of repeats by one of the single stroke devices and the corelative number and timing of inoperative periods of the 90 other device whereby repeating operations on a varying number of the lengths of the material may be selectively performed.

6. A machine for printing upon sheets of linoleum, impregnated felt and the like including a platen operating to print a body design on a sheet, another platen operating to print a border design on said sheet, detents associated with the body printing platen and automatically operable to retain 100 such platen in inactive position during the passage thereunder of a blank border space, other detents associated with the border printing platen automatically holding said platen inactive during the passage of a 105 printed body portion thereunder and permitting operation of the border platen on the border space and automatic controlling means for shifting the detents of both platens, including a rotatable detent shifting member and a member adjustable to 110 vary the speed of the rotatable member and consequently the number of repeats successively printed upon the body portion by the body platen and the number of corelative 115 inoperative periods of the other platen whereby similar patterns of varying body lengths may be selectively printed.

7. A printing machine, including a bed, a platen, means for intermittently feeding material to be printed upon under the platen, platen operating means working in synchronism with the material feed, a detent selectively operable to hold the platen against 125 operation and means controlled by the platen 130

operating means and including a rotatable element operative to shift the detent a predetermined number of steps for each releasing operation and means for varying the speed of the rotatable element relative to the platen operating means.

8. A printing machine, including a bed, a platen, means for intermittently feeding material to be printed upon under the platen, platen operating means working in synchronism with the material feed, a detent selectively operable to hold the platen against operation, means for rendering the detent operative after the platen has printed any desired number of repeats, said means comprising a ratchet wheel operable to shift the detent a predetermined number of times per revolution, means for varying the speed of the ratchet wheel relative to the speed of the feeding and printing mechanism and operative connections between the ratchet wheel and detent.

9. A printing machine, including a bed, a platen, means for intermittently feeding material to be printed upon under the platen, platen operating means working in synchronism with the material feed, a detent selectively operable to hold the platen against operation, means for rendering the detent operative after the platen has printed any desired number of repeats, said means comprising a ratchet wheel operable to shift the detent a predetermined number of times per revolution, means for varying the speed of the ratchet wheel relative to the speed of the feed and printing mechanism and operative connections between the ratchet wheel and detent, said connections including a cam driven by the ratchet and detent shifting means actuated by the cam.

10. A printing machine, including a bed, a platen, means for intermittently feeding material to be printed upon under the platen, platen operating means working in synchronism with the material feed, a detent selectively operable to hold the platen against operation and means for rendering the detent operative after the platen has printed any desired number of repeats, said means including a ratchet wheel operable to shift the detent a predetermined number of times per revolution, means for varying the speed of the ratchet wheel relative to the speed of the feed and printing mechanism and operative connections between the ratchet wheel and detent, said connections including a cam driven by the ratchet and detent shifting means actuated by the cam, said ratchet wheel including a plurality of sets of teeth, the teeth of the respective sets being spaced different distances apart, and a driving pawl selectively engageable with the successive teeth of any set whereby to permit selective timing of the detent shifting means.

11. A printing machine, including a bed, a platen, means for intermittently feeding material to be printed upon under the platen, platen operating means working in synchronism with the material feed, a detent selectively operable to hold the platen against operation, means for rendering the detent operative after the platen has printed any desired number of repeats, said means comprising a ratchet wheel operable to shift the detent a predetermined number of times per revolution, means for varying the speed of the ratchet wheel relative to the speed of the feeding and printing mechanism and operative connections between the ratchet wheel and detent, and means for driving the ratchet wheel from the platen operating means.

12. A printing machine, including a bed, a platen, means for intermittently feeding material to be printed upon under the platen, platen operating means working in synchronism with the material feed, a detent selectively operable to hold the platen against operation, means for rendering the detent operative after the platen has printed any desired number of repeats, said means comprising a ratchet wheel operable to shift the detent a predetermined number of times per revolution, means for varying the speed of the ratchet wheel relative to the speed of the feeding and printing mechanism and operative connections between the ratchet wheel and detent, said speed varying means including reciprocating rocking member carrying a driving pawl and means for varying the effective length of the feed stroke of the pawl.

13. A printing machine, including a bed, a set of body pattern printing platens each bearing a portion of a design and successively operable upon material passed thereunder, a set of border printing platens successively operable for printing different portions of a border design on said material, continuously operating driving means for the platens synchronized with the intermittent feed of the material, detents selectively engageable with the platens to hold them inactive, and means for timing the operation of the detents to prevent body printing on a border space and vice versa, including a ratchet wheel associated with each platen and intermittently driven by the platen operating means an adjustable device for determining the speed of the ratchet wheel and detent shifting means operated by the ratchet.

14. A printing machine, including a bed, a set of body pattern printing platens each bearing a portion of a design and successively operable upon material passed thereunder a set of border printing platens successively operable for printing different portions of a border design on said material, continu-

ously operating driving means for the platens synchronized with the intermittent feed of the material, detents selectively engageable with the platens to hold them inactive, 5 and means for timing the operation of the detents to prevent body printing on a border space and vice versa, including a ratchet wheel associated with each platen and intermittently driven by the platen operating 10 means, detent shifting means driven by the ratchet, and means for varying the distance which the ratchet is turned at each feeding movement whereby to predetermine the number and timing of the printing or non- 15 printing operations of the platens.

15. A printing machine, including a bed, a set of body pattern printing platens each bearing a portion of a design and successively operable upon material passed thereunder, a set of border printing platens successively operable for printing different portions of a border design on said material, continuously operating driving means for the platens synchronized with the intermittent feed of the material, detents selectively engageable with the platens to hold them inactive, and means for timing the operation of the detents to prevent body printing on a border space and vice versa, including a ratchet wheel associated with each platen and intermittently driven by the platen operating means, detent shifting means driven by the ratchet, and means for varying the distance which the ratchet is turned at each feeding movement whereby to predetermine the number and timing of the printing or nonprinting operations of the platens, said ratchet wheel having a plurality of series of teeth in its periphery, one tooth being common to all of the series and the teeth of the different series being spaced different distances apart. 20 25 30 35 40

16. A printing machine, including a bed, a set of body pattern printing platens each bearing a portion of a design and successively operable upon material passed thereunder, a set of border printing platens successively operable for printing different portions of a border design on said material, continuously operating driving means for the platens synchronized with the intermittent feed of the material, detents selectively engageable with the platens to hold them inactive, and means for timing the operation of the detents to prevent body printing on a border space and vice versa, including a ratchet wheel associated with each platen and intermittently driven by the platen operating means, detent shifting means driven by the ratchet, and means for varying the distance which the ratchet is turned at each feeding movement whereby to predetermine the number and timing of the printing or nonprinting operations of the platens, the intermittent feed for the ratchet including an oscillating pawl and means for varying the effective length of the feed stroke of the pawl. 45 50 55 60 65

over which the pawl may ride idly on a portion of its feed stroke.

17. A printing machine, including a bed, a set of body pattern printing platens each bearing a portion of a design and successively operable upon material passed thereunder, a set of border printing platens successively operable for printing different portions of a border design on said material, continuously operating driving means for the platens synchronized with the intermittent feed of the material, detents selectively engageable with the platens to hold them inactive, and means for timing the operation of the detents to prevent body printing on a border space and vice versa, including a ratchet wheel associated with each platen and intermittently driven by the platen operating means, detent shifting means driven by the ratchet, and means for varying the distance which the ratchet is turned at each feeding movement whereby to predetermine the number and timing of the printing or nonprinting operations of the platens, said ratchet wheel having a plurality of series of teeth in its periphery, one tooth being common to all of the series and the teeth of the different series being spaced different distances apart. 70 75 80 85 90 95

18. A printing machine, including a bed, a set of body pattern printing platens each bearing a portion of a design and successively operable upon material passed thereunder, a set of border printing platens successively operable for printing different portions of a border design on said material, continuously operating driving means for the platens synchronized with the intermittent feed of the material, detents selectively engageable with the platens to hold them inactive, and means for timing the operation of the detents to prevent body printing on a border space and vice versa, including a ratchet wheel associated with each platen and intermittently driven by the platen operating means, detent shifting means driven by the ratchet, and means for varying the distance which the ratchet is turned at each feeding movement whereby to predetermine the number and timing of the printing or nonprinting operations of the platens, and means for damping the feeding movement of the ratchet. 100 105 110 115 120

19. A printing machine, including a bed, a set of body pattern printing platens each bearing a portion of a design and successively operable upon material passed thereunder, a set of border printing platens successively operable for printing different portions of a border design on said material, continuously operating driving means for the platens synchronized with the intermittent feed of the material, detents selectively engageable with the platens to hold them inactive, and means for timing the operation of the detents to prevent body printing on a border space and 125 130 135 140

- vice versa, including a ratchet wheel associated with each platen and intermittently driven by the ratchet, and means for varying the distance which the ratchet is turned 5 at each feeding movement whereby to predetermine the number and timing of the printing or nonprinting operations of the platens, the sets of detent shifting means for the body printing platen and border printing platens 10 including reversely arranged cams driven by the ratchets.
20. The combination with a vertically reciprocable printing platen and a detent for holding the platen inactive on its printing stroke, of detent shifting means including a step by step mechanism, means for varying the speed thereof and a shifting cam driven from the step by step mechanism.
21. The combination with a vertically reciprocable platen and a detent for holding the platen inactive, of detent shifting means including a ratchet wheel, means for intermittently turning the ratchet wheel, means for optionally predetermining the distance 25 through which the ratchet wheel is turned at each step, a cam coupled to the ratchet wheel and operable to shift the detent upon each revolution of the ratchet wheel.
22. The combination with a vertically reciprocable platen and a detent for holding the platen inactive, of detent shifting means including a ratchet wheel, means for intermittently turning the ratchet wheel, a cam coupled to the ratchet wheel and operable to shift the detent upon each revolution of the ratchet wheel, and means for varying the distance through which the ratchet is fed whereby to selectively time the shifting cam.
- 40 23. The combination with a vertically reciprocable platen, and a detent for holding the platen inactive, of detent shifting means including a ratchet wheel, a shifting cam driven by the ratchet wheel, a pawl carrying arm for intermittently turning the ratchet wheel and means for varying the effective length of the feeding stroke of the pawl.
- 55 24. The combination with a vertically reciprocable platen, and a detent for holding the platen inactive, of detent shifting means including a ratchet wheel, a shifting cam driven by the ratchet wheel, a pawl carrying arm for intermittently turning the ratchet wheel and means for varying the effective length of the feeding stroke of the pawl, said means including a cover plate adjustable over the periphery of the ratchet wheel to prevent engagement of the pawl with the teeth of the ratchet wheel during a portion of its feeding stroke.
- 60 25. The combination with a vertically reciprocable platen, and a detent for holding the platen inactive, of detent shifting means including a ratchet wheel, a shifting cam
- driven by the ratchet wheel, a pawl carrying arm for intermittently turning the ratchet wheel and means for varying the effective length of the feeding stroke of the pawl, said means including a cover plate 70 adjustable over the periphery of the ratchet wheel to prevent engagement of the pawl with the teeth of the ratchet wheel during a portion of its feeding stroke, and means for locking the cover plate in various adjusted 75 positions.
26. The combination with a vertically reciprocable platen, and a detent for holding the platen inactive, of detent shifting means including a ratchet wheel, a shifting cam driven by the ratchet wheel, a pawl carrying arm for intermittently turning the ratchet wheel and means for varying the effective length of the feeding stroke of the pawl, said means including a cover plate 80 adjustable over the periphery of the ratchet wheel to prevent engagement of the pawl with the teeth of the ratchet wheel during a portion of its feeding stroke, and means urging the cover plate against the ratchet wheel to damp the movement thereof under the impetus of the pawl.
- 85 27. The combination with a vertically reciprocable platen and a detent for holding the platen inactive, of detent shifting means comprising a ratchet wheel, a shifting cam moving with the ratchet wheel, said ratchet wheel having a plurality of series of differently spaced teeth about its periphery, a reciprocatory pawl for feeding the ratchet wheel, a guard plate for regulating the effective length of the feed stroke of the pawl whereby the pawl may engage with the successive teeth of any set to effect intermittent feed of the ratchet.
- 90 100 105 28. The combination with a vertically reciprocable platen and a detent for holding the platen inactive, of detent shifting means including a ratchet wheel, a detent shifting cam moving with the ratchet wheel, said ratchet wheel having a plurality of series of differently spaced teeth about its periphery, a reciprocatory pawl for feeding the ratchet wheel, a guard plate for regulating the effective length of the feed stroke of the pawl whereby the pawl may engage with the successive teeth of any set to effect intermittent feed of the ratchet, said ratchet being adjustable independently of the guard plate to properly position the cam.
- 110 115 120 29. Detent shifting means for a machine of the class described, including a ratchet wheel and a shifting cam rigid with a common hub and means for imparting step by step rotary movement to the ratchet wheel to repeatedly bring the cam into shifting position, and means for predetermining the distance which the ratchet wheel is moved at each step.
30. Detent shifting means for a machine 125 130

of the class described, including a ratchet wheel and a shifting cam integral with a common hub and means for imparting step by step rotary movement to the ratchet wheel to repeatedly bring the cam into shifting position, said shifting means including an arm having reciprocatory rocking movement, a pawl on the arm for shifting the ratchet wheel, means for rendering a predetermined portion of the operative stroke of the pawl idle, said arm including a bearing sleeve at one end turning on the hub of the cam.

31. Platen detent shifting means for a machine of the class described, including a shifting cam, a ratchet wheel driving the cam, a reciprocatory pawl for actuating the ratchet wheel, and a cover plate adjustable over the periphery of the ratchet to render a portion of the feed stroke of the pawl ineffective.

32. Platen detent shifting means for a machine of the class described, including a shifting cam, a ratchet wheel driving the cam, a reciprocatory pawl for actuating the ratchet wheel, a cover plate adjustable over the periphery of the ratchet to render a portion of the feed stroke of the pawl ineffective, a notched locking plate, a latch on the cover plate engageable in the notches of the locking plate to retain the cover plate in adjusted position.

33. A device of the character described in claim 31 and wherein means are provided urging the cover plate against the ratchet wheel to exert a braking action thereon, and damping the movement of the ratchet caused by the pawl.

34. Platen detent shifting mechanism for a machine of the class described including in combination with the detent means tending to maintain the detent in one extreme posi-

tion, means adapted to move the detent to the other extreme position including a cam, a ratchet wheel driving the cam, a reciprocated pawl for actuating the ratchet wheel and means for rendering idle a predetermined portion of the feed stroke of the pawl.

35. A device of the character described in claim 34, wherein an adjustable ratchet wheel cover predetermines the effective feeding stroke of the pawl.

36. In detent shifting mechanism of the class described, a detent, a ratchet wheel having a plurality of differently spaced series of notches in its periphery, one of said notches constituting a zero notch and being common to all of the series, a reciprocatory member engageable in the notches to intermittently drive the ratchet wheel and a guard member adjustable over the periphery of the wheel to prevent engagement of the reciprocatory member in the notches during any desired portion of its feed stroke whereby said member may be caused to work in any of the series of notches to vary the feed of the ratchet, and operative connections between the ratchet and the detent.

37. Detent shifting means of the class described including a detent in combination with a ratchet wheel having a plurality of differently spaced series of notches in its periphery, one of said notches constituting a zero notch and being common to all of the series, certain of the other notches being common to a plurality of the series, means for rotating the ratchet wheel successively engageable in the notches of any predetermined series, and operative connections between the ratchet and the detent.

Signed at Kearny, in the county of Hudson, and State of New Jersey, this 29th day of July, A. D. 1924.

JAMES F. STURROCK.
